CLAIM

The ornamental design for a CD player case and attached belt, as shown and described.

DESCRIPTION

FIG. 1 is a front perspective view of a CD player case and attached belt, showing my new design, the broken lines representing stitching and forming no part of my claimed design;

FIG. 2 is a front elevation view of the invention illustrated in FIG. 1;

FIG. 3 is a left elevation view of the invention illustrated in FIG. 1;

FIG. 4 is a right elevation view of the invention illustrated in FIG. 1;

FIG. 5 is a top plan view of the invention illustrated in FIG. 1;

FIG. 6 is a bottom plan view of the invention illustrated in FIG. 1; and

FIG. 7 is a rear elevation view of the invention illustrated in FIG. 1; and,

FIG. 8 is a front perspective view of the invention shown in FIG. 1 with a front flap shown in an open position.

The broken line showing of environment are for illustrative purposes only and forms no part of the claimed design.
